Patented Oct. 31, 1972

225,031

MACHINE FOR ASSEMBLING BUTTONS

Malcolm J. Roebuck, La Salle, Ill., assignor to
First National Bank in Peru

Filed Mar. 4, 1971, Ser. No. 121,232

Term of patent 14 years

Int. Cl. D15—99

U.S. Cl. D55—1

FIG. 1 is a perspective view of a machine for assembling buttons, showing my new design;

FIG. 2 is a side elevational view of the side opposite to that shown in FIG. 1;

FIG. 3 is a front elevational view thereof;

FIG. 4 is a rear elevational view thereof; and

FIG. 5 is a top plan view thereof.

I claim:

The ornamental design for a machine for assembling buttons, as shown.
